(57) CLAIM

The ornamental design for a display screen or a portion thereof with a contact bowl graphical user interface, as shown and described.

DESCRIPTION

The FIGURE is a front view of a display screen or a portion thereof with a contact bowl graphical user interface as shown and described.

The outermost broken line represents a display screen or a portion thereof and forms no part of the claimed design. The remaining broken lines illustrate portions of the graphical user interface which form no part of the claimed design.
